UNITED STATES PATENT OFFICE.

JAMES K. P. PINE, OF TROY, NEW YORK, ASSIGNOR TO UNITED SHIRT AND COLLAR COMPANY, OF TROY, NEW YORK, A CORPORATION OF NEW YORK.

COLLAR.

1,101,091.

Specification of Letters Patent. Patented June 23, 1914.

Application filed September 10, 1909. Serial No. 517,103.

To all whom it may concern:

Be it known that I, JAMES K. P. PINE, a citizen of the United States, residing at Troy, Rensselaer county, New York, have invented certain new and useful Improvements in Collars, of which the following is a specification.

My invention relates to detachable shirt collars, such as are worn by men and boys, and particularly to "turn-down" collars of modern style, of which the "tops" or outer parts are brought close to or very near each other when the collar is buttoned. Such collars when stiffly starched are very difficult to button.

A principal object of my invention is to facilitate the buttoning operation.

In the drawings, Figure 1 is a front elevation of a collar embodying my invention in its buttoned position; Fig. 2 shows one end of this collar; Fig. 3 is a view like that of Fig. 2, showing a modification.

Referring to Figs. 1 and 2 of the drawings, 11 designates a collar of "turn-down" pattern, of which 12 is the band and 13 the top or outer part. The right end, as worn, of the band 12 is provided with a tab 14 of ordinary form, having a button-hole 15, which may be of the usual form, for engagement with a collar stud 16 in the neck-band of the shirt. The tab 17 at the left end of the band, as worn, the right as shown in the drawing, is, as is customary, considerably longer than the tab 14, and, as here shown, 35 has the curved upper edge and sharp corner distinguishing the "lock collar," for which U. S. Patent #882,415 was granted to me on March 17, 1908. The button-hole 18 in this tab 17 is formed at an acute angle with the usual horizontal line and is so positioned in the tab that its inner, lower end is at approximately the same distance from the upper edge of the band 12 as the outer end of the button-hole 15 in the other tab 14, 40 whereby this inner, lower end of the button-hole 18 engages with the shank of the stud 16 when the collar is in its normal buttoned or worn position, in which the upper corners of the top 13 are horizontally alined as shown in Fig. 1. It may advantageously be provided with an eyelet 19 at its inner end and with an enlarged portion 20 at its upper, outer end, see Fig. 2.

In attaching the front ends of the collar

11 to a shirt band, the shorter tab 14 is first 55 buttoned on the stud 16 in the neck-band; the tab 17 may then be slipped partially under the fold of the collar, but not inwardly or upwardly to its normal position, so that the button-hole 18 may be engaged with the 60 stud at least as easily as if the close collar shown were of an open pattern, *i. e.*, one with its top ends normally separated; and, of course, more easily than where a straight button-hole, like 15, is provided, by reason 65 of the fact that the enlarged portion 20 passes without considerable distortion over the head of the stud 16. When the left end of the collar is then raised to its proper position, as in Fig. 1, the eyelet 19 embraces 70 the shank of the stud 16 (or, of course, the attaching threads of a button if this is used) and assists in retaining the collar in its proper position until the strap of the cravat or tie is drawn taut.

In Fig. 3 of the drawings, a modification of the form of the button-hole in the outer or longer tab 17 is shown, which consists in forming an eyelet 29 at the inner, lower end of the hole, not in the usual axial line therewith, but at one side of the line thereof, in the present instance, at the inner, upper side.

It will be seen that by reason of the enlarged portion 20 of the button-hole, it will be very easily engaged with the stud; and 85 that the non-alined eyelet 29 will embrace the shank of the stud so as to materially resist displacement of the end of the collar, particularly if the collar is of the "lock" pattern shown and the eyelet is placed, as 90 shown, above the slotted portion of the hole, whereby the engagement of the upper edge of the tab within the fold of the collar resists the slight upward movement of the tab necessary to unbutton it.

It will be understood that while the invention is especially advantageous in connection with the "lock collar" of my prior patent, no form of collar is, *per se*, essential to my invention.

By the word "button-hole," as used in the specification and claims hereof, I intend a closed hole, entirely within and inclosed by the fabric of the band or tab, as distinguished from a slot or notch opening from 105 the edge thereof.

What I claim is:

1. A turn-down collar having tabs, one of

which is adapted to fit snugly within the fold of the collar when in its buttoned position, said last-named tab being provided with an angularly disposed button-hole entirely within and inclosed by the fabric of the tab and having an eyelet at its inner end adapted to embrace the shank of a collar stud, and an enlarged portion at its outer end, said eyelet and said enlarged portion

10 being connected by a slotted portion, substantially for the purposes set forth.

2. A turn-down collar having tabs, one of which is adapted to fit snugly within the fold of the collar when in its buttoned position, said last-named tab being provided with an angularly disposed button-hole entirely within and inclosed by the fabric of the tab and having an eyelet at its inner end adapted to embrace the shank of a collar

15 stud, and an enlarged portion at its outer end adapted to pass over the head of such stud, said eyelet and said enlarged portion

being connected by a slotted portion, substantially for the purposes set forth.

3. A turned down lock front collar having the usual locking tab, said tab having a button-hole provided with an enlarged opening, a slit extending downwardly therefrom and a recess located at the lower end of the slit for the reception of the shank of the collar button.

4. A turned down lock front collar having the usual locking tab, said tab having a button-hole provided with an enlarged opening, a slit extending downwardly and inwardly therefrom and an eyelet at the lower end of the slit and at the upper, inner side thereof for the reception of the shank of the collar button.

JAMES K. P. PINE.
